UNITED STATES PATENT OFFICE.

GEORGE F. HUTCHINS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOOM FOR WEAVING TUFTED FABRIC.

1,142,170.

Specification of Letters Patent.

Patented June 8, 1915.

Application filed May 28, 1914. Serial No. 841,611.

To all whom it may concern:

Be it known that I, GEORGE F. HUTCHINS, a citizen of the United States, residing at Worcester, in the county of Worcester and 5 State of Massachusetts, have invented a new and useful Loom for Weaving Tufted Fabric, of which the following is a specification.

This invention relates to looms for weaving tufted fabrics of the type shown and described in United States Letters Patent No. 10 490,237, in which tuft yarn carriers or spools are successively moved into position to supply the tuft yarn for forming the fabric.

In a loom of this type the full number of 15 tuft yarns to constitute the tuft filling for the entire width of the rug for a single pick are wound upon one or more spools arranged in axial alinement upon a tuft yarn carrier. Each separate tuft yarn is brought down 20 into a yarn tube, these tubes being arranged in adjacent parallel relation upon the carrier.

The carriers which contain the required tuft yarn for the successive picks of the 25 design are detachably mounted upon a carrier chain and provision is made for successively detaching the separate carriers from the chain and for moving the detached carrier downward to carry the tuft yarn in the 30 tubes between the warp threads thereby causing the ends of the tufted yarns to be inserted between the warps. The carrier and tubes are thereafter raised and the tuft yarns are cut off at the proper length to form the 35 pile of the fabric. In order that the severed pieces of yarn may be of uniform length and that only the necessary amount of yarn shall be cut off at each operation, it has been customary to provide friction devices 40 engaging the carrier spools for retarding the unwinding of the yarn. This method of construction is reasonably satisfactory until one or more of the tuft yarns becomes nearly exhausted upon the spool. When this occurs the yarn will slip freely through the 45 tubes and an irregular and excessive length of yarn may be thus inserted in the design. To prevent this occurrence it is necessary to replenish the spools as soon as any of the 50 tuft yarns become loosened in the manner described. As a particular tuft yarn ordinarily comes into operative position only once or twice during the weaving of each rug design, it is evident that only a short

length of each tuft yarn is required for each 55 rug. The length of each yarn wasted by the procedure outlined has been found sufficient to supply that particular part of the design for several additional rugs.

It is the object of my invention to provide 60 improved means for retarding the feeding of the tuft yarns through the tubes, independently of the friction exerted upon the carrier spools, to the end that the yarn may be used substantially to its full length be- 65 fore replenishment becomes necessary.

With this object in view my invention consists in the improved friction device which will be hereinafter described and more particularly pointed out in the ap- 70 pended claims.

A preferred form of my invention together with a modification thereof is shown in the drawings, in which—

Figure 1 is a side elevation showing a 75 portion of a carrier with the yarn tubes and spool mounted thereon; Fig. 2 is a view similar to Fig. 1 but showing the yarn upon the spool exhausted; Fig. 3 is an enlarged sectional view of certain of the yarn tubes; 80 Fig. 4 is a transverse sectional view taken along the line 4—4 in Fig. 3; and Figs. 5 and 6 are sectional and side elevations of a modified form of my friction device.

In Fig. 1 I have shown a carrier 10 with 85 a spool 11 rotatably mounted thereon. The spool is provided at each end with a gudgeon which turns within a recess in an upwardly extending arm 12. A spring arm 13 provides means for detachably securing the carrier 90 to the carrier chain (not shown). A second spring arm 14 supports a disk 15 which frictionally engages the head of the spool 11.

A spring plunger 16 is slidably mounted 95 in an arm 17 and is supported in position to engage the outer side of the disk 15. The arm 17 is operatively connected to the trans- 100 ferrer mechanism by which the carrier is removed from the chain and lowered to its operative position. These connections act to 100 force the plunger 16 against the disk 15 as the carrier is lowered. The tuft yarns A are wound upon the spool 11 and extend downwardly therefrom through the tuft 105 yarn tubes 20 which are secured to the car- rier 10 in adjacent parallel relation.

The parts thus far described constitute no part of my invention and for a full de-

scription thereof reference may be had to United States Letters Patent No. 1,033,589, granted to me on July 23, 1912.

In order to prevent the free passage of the tuft yarns through the tubes when they are loosened from the spool, as shown in Fig. 2, I provide the friction devices shown in Figs. 3 to 6 inclusive.

In the form shown in Fig. 3 each friction device comprises a U-shaped member 21 formed of resilient material. When in operative position, each member embraces one side of each of two adjacent tubes 20 between its parallel depending portions. At their lower ends, the depending portions of the friction device 21 are convexly curved so that they form a constricted passage within each tube, the convex portions frictionally engaging the yarn as it is drawn through said passage. By this means the friction upon the yarn is to a large extent independent of the friction upon the spool and each tuft yarn can be used until its upper end passes below its friction devices 21. By this method of procedure the amount of waste yarn is reduced to a negligible quantity.

In the form shown in Fig. 3 the friction members are retained in position upon the tubes by a transverse bar 22 which is secured to the carrier itself in any convenient manner and engages the tops of the friction members.

In the modified form shown in Fig. 5, the upper end of each friction member is enlarged at 23 and the upper edges of the tubes 20 are bent outwardly as at 24 within said enlargement thereby retaining the friction device in operative position without the use of the bar 22. As the friction members are formed of resilient material and the tubes themselves are of thin sheet material the tubes may be bent to the form shown in Fig. 5 before the friction devices are snapped into place.

Having thus described my invention it will be evident that many changes and modifications may be made therein without departing from the spirit and scope of my invention as set forth in the claims and I do

not wish to be limited to the details herein disclosed, but

What I do claim is:—

1. In a loom for weaving tufted fabrics, in combination, a plurality of yarn tubes, 55 and separate friction members supported by said yarn tubes, each frictionally engaging the tuft yarn in two adjacent tubes at points within said tubes to retard the passage of the yarn therethrough. 60

2. In a loom for weaving tufted fabrics, a carrier supporting a supply of tuft yarn, a plurality of yarn tubes supported adjacent to said carrier, a spring friction device comprising a U-shaped friction member embracing one side of each of two adjacent tubes, and means to retain said member in operative position. 65

3. In a loom for weaving tufted fabrics, a carrier supporting a supply of tuft yarn, 70 a plurality of yarn tubes supported adjacent to said carrier, spring friction devices each comprising a U-shaped friction member embracing one side of each of two adjacent tubes, and means to retain said devices in 75 operative position, the depending portions of said U-shaped members being convexly curved at their lower ends to frictionally engage the yarn.

4. In a loom for weaving tufted fabrics, 80 in combination, a carrier supporting a supply of tuft yarn, a plurality of yarn tubes supported adjacent to said carrier, and spring friction devices each comprising a U-shaped friction member embracing one 85 side of each of two adjacent tubes, each member having an enlargement at its upper end and the sides of said tubes being curved outwardly at their upper ends within said enlargement and being thus effective to retain the friction member in operative position. 90

In testimony whereof I have hereunto set my hand, in the presence of two subscribing witnesses.

GEORGE F. HUTCHINS.
